UNITED STATES PATENT OFFICE

2,681,002

WIRE PULL-OFF FOR HAY BALERS

Robert J. Good, Hopkins, Minn., assignor to Minneapolis-Moline Company, Hopkins, Minn., a corporation of Minnesota

Application January 3, 1950, Serial No. 136,509

11 Claims. (Cl. 100—21)

1

This invention relates generally to improvements in baling machines and more particularly to automatic hay balers of the type disclosed and claimed in co-pending application Serial No. 530,796 for Baling Machine, filed April 13, 1944, now Patent No. 2,548,559, issued April 10, 1951, and in which patent and the instant application there is a common assignee.

The present application further relates to certain improvements over the somewhat similar mechanism disclosed in co-pending application Serial No. 705,716 for Wire Feed for Hay Balers, filed October 25, 1946, now Patent No. 2,604,845, issued July 29, 1952, also to the same assignee. These related applications are directed to the solution of the same problem in the operation of automatic hay balers, which problem results from a tendency of the reciprocating baling plunger to impart such sharp movements to the tying wires as either to break the wires or cause overrunning of the wire feed mechanism itself. In the previous application the wires were arranged over movable guide rollers in such manner that slack could be accumulated in the wire on the back stroke of the plunger, but I find that the movement of such guide rollers directly by the plunger itself, as was disclosed in that application, is itself so abrupt that difficulties are encountered. In accordance with the primary object of my present invention therefore I employ similar guide means for the wires but move the same in response to the operation of another part of the machine in such manner as to obtain a more gradual acceleration of the movement and completely overcome any tendency towards breakage of the wires or any other undesirable effects thereon.

It is, of course, necessary that the slack be developed in the wires in timed relation to the reciprocating movements of the plunger in order that the slack will be ready and waiting as the plunger moves on its compression stroke into the baling chamber, forcing the hay into compacted condition and pulling off wire from the wire feed mechanism of the baler. In the machine here involved there is embodied a packer head which has the function of packing hay into the chamber in advance of each compression stroke of the plunger and this packer head is arranged upon an oscillating frame which operates in synchronism with the plunger movements, as is obviously necessary. As a further object of my invention therefore I operate the wire pull-off guide means or rollers by such oscillating movements of the packed head and embody in the linkage con-

2

necting the rollers and the packer a swinging connection which is so arranged as to cause the desirable gradual acceleration of the roller movement as has been previously described.

Still another object of my present invention is to provide means whereby the amplitude of the guide roller movements may be readily regulated in order to correspondingly regulate the amount of slack pulled off from the wire feed mechanism for each cycle of operation. Such adjustments are advantageous in that compensation may be made thereby for heavy or light crop feed rates and for the differing characteristics which may be encountered in the wire used for tying.

These and other more detailed and specific objects will be disclosed in the course of the following specification, reference being had to the accompanying drawings, in which—

Fig. 1 is a plan view of a central portion of an automatic hay baler of the type involved in this invention and particularly illustrating the manner in which the tying wires are run into the baling chamber over the pull-off or guide rollers.

Fig. 2 is a side elevation of the central portion of the baler showing the wire pull-off mechanism and its connections to the packer head and showing the latter in its elevated position withdrawn from the baling chamber.

Fig. 3 is a similar view but showing the parts in the positions assumed as the packer head enters the baling chamber in advance of the plunger and with the pull-off rollers moved to positions for drawing off slack from the wire feed mechanism.

Fig. 4 is a horizontal sectional view through the baling chamber and associated parts and illustrating the baling plunger on its return or back stroke.

Fig. 5 is a similar view and showing the plunger upon its working or compression stroke.

Fig. 6 is an enlarged sectional detail view along the line 6—6 in Fig. 2.

Referring now more particularly and by reference characters to the drawing, A designates generally the frame of the baling machine, which is supported for travel movement over the field upon wheels B and has means C for picking up hay and depositing it through a feed opening D downward into a baling chamber E formed in the frame A. A baling plunger F is reciprocably mounted in the chamber E for periodic movement from a normal position forward of the feed opening D through a working or compression stroke rearwardly into the baling chamber

E to thereby force wads or bunches of hay received from opening D in a rearward direction and compress the hay into bales as will be readily understood. The bales are tied at vertically spaced points by encompassing wires which are fed into one side of the baling chamber through openings G shown in Fig. 2, in which view the tying wires are also indicated at H—H'. While in Figs. 1, 3 and 4 only the uppermost wire H appears, it will be understood that the lower wire H' and all associated supply means therefor are identical to those now to be described for the upper wire H.

The wire H is taken from a continuous length coiled upon a spool I and fed through an anti-backlash mechanism J, and to and through a needle K hinged at L upon the adjacent side of the frame A. The wire passing from the swinging end of the needle K is carried inwardly over a guide roller M and at the outset of baling operations is stretched directly across the baling chamber E over a pin N which forms part of a tying mechanism, designated generally at O. The tying mechanism holds this end of the wire and it will then be understood that as hay is forced into the chamber by the plunger F it will strike the wire where it traverses the baling chamber and will pull wire through the needle K and mechanism J from the spool I as required by the increasing length of the bale. When a bale of the desired length has been accumulated, mechanism not important to the present invention, swings the needle K through the baling chamber to bring a portion of the wire into overlapping engagement with the end held in the tying mechanism O which then twists these overlapping wires together to complete the tying of the bale. The needle then returns to the position shown in Fig. 1 leaving wire stretched across the baling chamber ready for tying the next bale.

The mechanism thus far described is substantially identical to that disclosed in the prior patents hereinbefore identified and no further description herein is believed to be necessary. It will be understood, however, that each time the plunger F compresses and forces a wad of hay into the baling chamber, these wads, coming in contact with the tying wires, will pull the wires into the chamber through the needles K and mechanism J and from the spools I. It is found that there is sufficient resistance through all of these mechanisms to so retard the advance of the wires that the sharp jerks imparted thereto each time the plunger approaches the bale with a new wad of hay sometimes causes a wire to be broken. This is of course extremely undesirable since it is the purpose of these inventions to provide a baler capable of operation rapidly and effectively without attendance of anyone in connection with the tying of the bales.

The baler further includes an oscillating packer device or mechanism, designated generally at P, comprising a frame having side members Q which are fulcrumed at R upon uprights S secured atop the baler frame A. At the rear ends the side members Q carry the packer head proper indicated at T, and the forward ends of the side members are connected by a link U to the pitman V which operates the plunger F. It will thus be understood that the rearward movement of the plunger F on its working or compression stroke will pull the link U forwardly so as to elevate the packer T, whereas the return

motion of the plunger will elevate the link U to thrust the packer head down through the feed opening E as shown in Fig. 3. The packer head is thus thrust downwardly from its normal position into the baling chamber in advance of the plunger F in order to pack hay or other material, received from the pick-up and feed mechanism C, into the chamber and the movements of the packer head are obviously timed with reference to the reciprocation of the plunger.

The aforesaid guide roller M, and its corresponding roller M' for the lower tying wire, operate to pull out slack from the wires in accordance with my invention and for this purpose the rollers are journaled upon upper and lower support bars 10 and 11 secured together in vertically spaced relation as indicated generally at 12 and carried upon a reciprocating rod 13 mounted along the right hand side of the baler frame A. To slidably support the rod 13 I provide slide bearings 14 secured to the frame and the rollers M—M' are positioned adjacent and in horizontal alignment with the openings G so that the wires may pass from the needles K forwardly and then rearwardly around the rollers into the baling chamber E. As best shown in Fig. 1 the tying wires form a loop between the rollers and the pins N so as to encompass the sides and rear end of the accumulating bale. It will be apparent that each working stroke of the plunger F will lengthen the wire in the loop around the sides and rear of the bale and the difficulties which my invention solve have arisen from the fact that this successive lengthening action on the wires has on occasion caused breakage or overrunning effects due to the abruptness with which the action takes place. The movable support for the rollers M—M' as described makes it possible, however, upon each return motion of the plunger to pull off wire from the needles so that sufficient slack is provided to prevent these undesirable effects. For this purpose the rollers M—M' are moved forwardly a short distance upon each return stroke of the plunger and are then restored to their normal position leaving the desired slack in the wire from the ends of the needles to the rollers as will be understood.

In accordance with my invention I attach to the forward end of the rod 13 a yoke fitting 15 having a tubular portion 16 to accommodate the rod so that it may be secured thereto by nuts 17 as clearly shown in Figs. 2 and 3. At its forward end the fitting 15 has a vertically elongated slot 18 in which there plays a pin 19 extending inwardly from the lower arm 20 of a bell crank lever 21 fulcrumed at 22 upon the baler frame above the forward end of the rod. This bell crank lever has a forwardly projecting arm 23 to which the lower end of a link rod 24 is pivoted at 25. The upper end of the rod 24 may be pivotally attached at 26 to any one of a series of openings 27 formed in the outer end 28 of a bracket 29 which is secured by bolts 30 to one of the side members Q of the packer frame. The bracket 29 has an L-shaped formation to accommodate it to such attachment, and the end 31 of the bracket fitted to the side frame Q may be separated therefrom by a shim plate 32 in order to properly align this bracket structure with the bell crank lever 21 as seen in Fig. 6.

This linkage mechanism is thus so arranged that in the normal or withdrawn position of the packer head T, which it assumes when the plunger F is on its compression stroke, the rollers

M—M' will be in their rearmost positions. This is, of course, due to the fact that the bracket 29 is attached to the packer frame forwardly of its fulcrum point R and in such position of the packer the bell crank lever 21 will be oscillated in a clockwise direction to thrust the support rod 13 rearwardly. Now as the plunger F moves on its return stroke the link U will start the packer head downwardly to feed material into the baling chamber and the resulting upward motion of the forward portion of the packer frame will exert a pull upon the link rod 24 such as to oscillate the bell crank lever 21 in the opposite direction and towards the position of Fig. 3. Such motion of the bell crank lever will cause its lower arm 20 to swing forwardly and the pin 19 playing in slot 18 will pull the fitting 15 and associated rod 13 forward so that the rollers will pull off slack in the tying wires. The motion imparted to the rollers and their support results from a swinging or arcuate travel of the bell crank 21 and thus there will be a gradual acceleration, as compared to the more direct and reciprocating connection between the support and the baling plunger as disclosed in Patent No. 2,604,845. Thus I completely overcome the tendency of the pull-off mechanism itself either to break the wires or to pull them off with such rapidity as to cause difficulties in the wire feed mechanism per se. The slot 18 compensates for the up and down motion of the pin 18 in translating the swinging movement of the bell crank lever to reciprocating movement of the support rod 13, while the provision of a series of openings 27 for the attachment of the upper end of the link rod 24 enables me to control the amplitude of the various motions involved and correspondingly regulate the amount of slack wire pulled off during each operation. For this purpose the openings 27 for attachment of the link rod are spaced apart with reference to the axis or fulcrum R upon which the packer swings, while the plate 23 is so angled with respect to the packer frame that these openings 27 stand in a substantially horizontal plane when the packer is in its withdrawn position as seen in Fig. 2. Thus changes in the position of the link rod 24, to regulate the distance through which the rollers M—M' are moved, will not substantially vary the normal position of the rollers as will clearly be understood.

Inasmuch as the operation of the packer is synchronized with that of the baling plunger it will be evident that the pull-off operation may be accurately timed so as to produce slack in the tying wires in advance of each working stroke of the plunger and it will be clearly evident from the foregoing and from the drawing that the actuation of the pull-off mechanism of the packer enables me to obtain a gradual acceleration of the motion such as to completely overcome difficulties encountered with the previous mechanism.

It is understood that suitable modifications may be made in the structure as disclosed, provided such modifications come within the spirit and scope of the appended claims. Having now therefore fully illustrated and described my invention, what I claim to be new and desire to protect by Letters Patent is:

1. The combination of a hay baler having a baling chamber and a reciprocating plunger therein, means for feeding a wire into the chamber around a bale as it is formed therein, and a packer device movable to pack hay into the chamber in advance of the plunger; of a roller ar-

ranged to guide the wire into the chamber, a movable support for the roller, and linkage connecting the packer device and said support for moving the roller and pulling off slack in the wire preliminary to reciprocation of the plunger.

2. The combination in a hay baler having a baling chamber and a reciprocating plunger therein, means for feeding a wire into the chamber around a bale as it is formed therein, and a packer device movable to pack hay into the chamber in advance of the plunger; of a roller arranged to guide the wire into the chamber, a movable support for the roller, and linkage connecting the packer device and said support to move the roller first in one direction to develop slack in the wire and then in the opposite direction to release the slack as the plunger moves into the chamber.

3. In a hay baling machine having a baling chamber, a reciprocating plunger in the chamber, a packer for packing hay into the chamber in advance of the plunger, and means for introducing at least one wire into the chamber and for stretching said wire across the chamber to encompass the bale as it is formed therein, guide means for the wire entering the chamber, a movable support for said guide means, and means connecting said support and packer for operating the guide means to accumulate slack in the wire prior to each working stroke of the plunger.

4. In a hay baler having a baling chamber and a reciprocating plunger and a wire supply for feeding a wire into the chamber around a bale responsive to the force exerted by the bale as it is accumulated by successive compression strokes of the plunger, a packer movable toward and away from the chamber in synchronism with the plunger strokes, wire pull-off means engaging the wire between the wire supply and chamber, a movable support for the wire pull-off means, and means including a swingable element for connecting the packer and said support to move the wire pull-off means in advance of each compression stroke of the plunger and pull off slack in the wire.

5. In a hay baler having a baling chamber and a reciprocating plunger and a wire supply for feeding a wire into the chamber around a bale responsive to the force exerted by the bale as it is accumulated by successive compression strokes of the plunger, a packer movable toward and away from the chamber in synchronism with the plunger strokes, wire pull-off means engaging the wire between the wire supply and chamber, a movable support for the wire pull-off means, means including a swingable element for connecting the packer and said support to move the wire pull-off means in advance of each compression stroke of the plunger and pull off slack in the wire, and means for adjusting the amplitude of movement of said swingable element to thereby regulate the length of wire pulled off.

6. In a hay baler having a baling chamber and a reciprocating plunger and a wire supply for feeding a wire into the chamber around a bale responsive to the force exerted by the bale as it is accumulated by successive compression strokes of the plunger, a packer movable toward and away from the chamber in synchronism with the plunger strokes, wire pull-off means engaging the wire between the wire supply and chamber, a movable support for the wire pull-off means, a bell-crank lever connected to said support, and a link connecting the lever to the packer for moving the

wire pull-off means in synchronism with the plunger.

7. In a hay baler having a baling chamber and a reciprocating plunger and a wire supply for feeding a wire into the chamber around a bale responsive to the force exerted by the bale as it is accumulated by successive compression strokes of the plunger, a packer movable toward and away from the chamber in synchronism with the plunger strokes, wire pull-off means engaging the wire between the wire supply and chamber, a movable support for the wire pull-off means, a swingable bell-crank lever connected to the support, a bracket member on the packer, and a link connecting the lever and bracket member for connecting the lever and bracket member for moving the wire pull-off means in synchronism with the movements of the packer and plunger.

8. In a hay baler having a baling chamber and a reciprocating plunger and a wire supply for feeding a wire into the chamber around a bale responsive to the force exerted by the bale as it is accumulated by successive compression strokes of the plunger, a packer movable toward and away from the chamber in synchronism with the plunger strokes, wire pull-off means engaging the wire between the wire supply and chamber, a movable support for the wire pull-off means, a swingable bell crank lever connected to the movable support, a bracket member on the packer, and a link connecting the bell crank lever and bracket member for moving the wire pull-off means in synchronism with the movements of the packer and plunger, the said bracket member having a series of spaced connections for connection of the link so arranged as to adjust the motion of the bell crank lever and wire pull-off means.

9. In a hay baler having a baling chamber and a reciprocating plunger and a wire supply for feeding a wire into the chamber around a bale responsive to the force exerted by the bale as it is accumulated by successive compression strokes of the plunger, a packer movable from a normal position toward and away from the chamber in synchronism with the plunger strokes, wire pull-off means engaging the wire between the wire supply and chamber, a movable support for the wire pull-off means, a swingable bell crank lever connected to the movable support, a bracket member on the packer, and a link connecting the bell crank lever and bracket member for moving the wire pull-off means in synchronism with the movements of the packer and plunger, the said bracket member having a series of spaced connections for connection of the link so arranged as to adjust the motion of the bell crank lever and

wire pull-off means, and said connections on the bracket member being all substantially equidistant from the bell crank lever in the normal position of the packer so that such adjustments may be made without themselves substantially altering the position of the bell-crank lever and connected pull-off means.

10. In a hay baler having a baling chamber and a reciprocating plunger and a wire supply for feeding a wire into the chamber around a bale responsive to the force exerted by the bale as it is accumulated by successive compression strokes of the plunger, an oscillatable packer for packing material into the chamber in advance of each compression stroke of the plunger, wire pull-off means engaging the wire, a reciprocating support for said wire pull-off means, a bell crank lever connected to said support and operative to reciprocate the same and pull the wire pull-off means from a normal position to draw slack wire from the supply and then return the wire pull-off means to said normal position, and a connection between the lever and the packer for swinging the lever.

11. In a hay baler having a baling chamber and a reciprocating plunger and a wire supply for feeding a wire into the chamber around a bale responsive to the force exerted by the bale as it is accumulated by successive compression strokes of the plunger, an oscillatable packer for packing material into the chamber in advance of each compression stroke of the plunger, wire pull-off means engaging the wire, a reciprocating support for said wire pull-off means, a bell crank lever connected to said support and operative to reciprocate the same and pull the wire pull-off means from a normal position to draw slack wire from the supply and then return the wire pull-off means to said normal position, and a connection between the lever and the packer for swinging the lever, and means for adjusting said connection to regulate the range through which the wire pull-off means is reciprocated while leaving the normal position thereof unchanged.
